ABSTRACT OF THE DISCLOSURE

An analytical instrument including a flame source and a detection system for the qualitative and quantitative emission or absorption analysis of a sample. The sample is atomized and mixed with an appropriate fuel gas, and the mixture is led through an angularly disposed burner barrel to a grid for holding the flame. Compressed air is supplied to the atomizer, and a portion of the air is directed to a venturi nozzle which is connected to a supply of the fuel gas. The air is effective to draw the fuel gas through the venturi and into the atomizer at a substantially constant rate irrespective of pressure fluctuations in a gas supply. The instrument additionally includes a screen and baffle construction within the angularly extending barrel which is effective to direct large droplets of sample material away from the barrel inlets.

This invention relates to analytical instruments and more particularly to flame analyzers adapted for use in flame photometric equipment, such as flame emission and absorbent devices.

There has been developed a flame analyzer and flame source therefor which enables the making of highly accurate analytical measurements in a rapid and straightforward manner. One such analyzer and flame source is disclosed in John U. White U.S. Pat. No. 2,664,779. As is well known, instrumentation of this type includes an atomizer for atomizing a sample of material to be analyzed and a burner which provides a pure flame for heating the atomized sample. The intensity of the flame is a function of the amount of the sample which is present. Accordingly, by measuring the emitted light from the flame, as by a suitable photoelectric detection system, the sample may be quantitatively evaluated. Similarly, since atoms and molecules of a given substance emit light of a characteristic wave length in response to heat, the presence or absence of the substance may be ascertained by utilizing a monochromator or filter to detect the emitted light from the flame at the selected wave length. The flame also may be analyzed by measuring the light absorbed thereby from an external source, to provide generally similar quantitative or qualitative evaluations of the sample. The term "light" as used herein, is intended to include, in addition to visible light, radiation having wave lengths both longer and shorter than the visible spectrum.

The detection systems for instruments of the foregoing type have high sensitivity, and even comparatively small variations in the flame may lead to errors of large magnitude. For example, the instruments are adversely affected by such factors as variations in the rate at which the fuel gas is supplied to the burner. It of course would be desirable for purposes of simplicity and economy to utilize natural or other fuel gas from the public gas mains. However, in the absence of complicated and expensive pressure regulators, mechanical pumps, etc., the normal variations in pressure from these mains have seriously impaired the accuracy of the analytical measurements.

In addition, in several types of flame analyzers employed heretofore, droplets of the sample material have exhibited a tendency to collect in the vicinity of the atomizer and the gas inlets. The droplets contaminated further

2

atomized samples and thus detracted from the accuracy of the readings, with the result that the apparatus required frequent cleaning. As another source of contamination in prior analytical instruments, unwanted residues frequently were deposited on the interior of the chimney for the burner portion of the apparatus and further reduced the accuracy of the readings.

One general object of this invention, therefore, is to provide a new and improved analytical instrument for the qualitative and quantitative emission analysis of a sample.

More specifically, it is an object of this invention to provide an analytical instrument of the character indicated in which the flame for exciting the substance being analyzed is supplied with fuel gas at a substantially constant rate irrespective of pressure fluctuations in the fuel gas supply.

Another object of the invention is to provide a flame analyzer for an atomized sample in which the analysis being made is substantially unaffected by any large droplets of the sample.

A further object of the invention is to provide flame analyzing apparatus in which the deposit of unwanted residue from the flame is substantially reduced.

Still another object of the invention is to provide a novel analytical instrument of improved accuracy which is economical to manufacture and thoroughly reliable in operation.

In one illustrative embodiment of the invention, the apparatus includes an atomizer for receiving a solution containing the sample to be analyzed. A burner grid is disposed in spaced juxtaposition with the atomizer and is connected thereto by an elongated barrel. A suitable fuel gas is mixed with the atomized sample, and the mixture is directed along the barrel to the grid where a substantially clean flame representative of the sample is produced. The flame is monitored by a photoelectric detection system which is responsive to one or more characteristics of the flame to produce an analytical measurement of the characteristic.

In accordance with one feature of the invention, there is provided novel venturi means which is supplied with the fuel gas and communicates with the atomizer. A pressurized stream of air or other combustion supporting gas draws the fuel gas through the venturi and into the burner barrel at a substantially constant rate irrespective of pressure fluctuations in the fuel gas supply. With this arrangement, the detected flame is unaffected by random changes in pressure of the fuel gas.

In accordance with another feature of the invention, in certain advantageous embodiments, a portion of the barrel between the atomizer and the burner grid is disposed at an angle with respect to the horizontal and is provided with a drain outlet adjacent its lower end. This outlet is oriented with respect to the fuel gas inlet and the atomizer such that any large droplets of spray from the atomized sample are automatically removed from the apparatus without clogging or otherwise interfering with either the inlet or the atomizer.

In accordance with a further feature of the invention, in several good embodiments, a screen and baffle structure of unique construction and arrangement is disposed within the barrel and is effective to channel the condensed droplets of sample material toward the drain, thereby further reducing the possibility of interference with the fuel gas inlet and the atomizer. The orientation of the baffle within the barrel is such that any large unatomized droplets similarly are deflected toward the drain prior to reaching the flame.

In accordance with still another feature of the invention, in some embodiments, a supply of clear air or other gas is continuously fed to the lower portion of the burner

chimney. The flow of gas is directed along the inside of the chimney to minimize the formation of unwanted residue thereon and to stabilize the flame.

The present invention, as well as further objects and features thereof, will be understood more clearly and fully from the following description of a preferred embodiment, when read with reference to the accompanying drawings, in which:

FIG. 1 is a schematic representation, with certain portions shown in section, of an analytical instrument in accordance with one illustrative embodiment of the invention;

FIG. 2 is an enlarged vertical sectional view of an atomizer and burner assembly for the instrument; and

FIG. 3 is an end elevational view of a portion of the atomizer, as seen from the line 3—3 in FIG. 2.

Referring to FIG. 1 of the drawings, there is shown an analytical instrument which comprises a funnel-shaped container 10 for the sample to be analyzed, a combined atomizer-burner having an atomizing section 12, an angularly disposed tube or barrel 14, a burner grid section 16, and a photoelectric detection system 18. As will become more fully apparent hereinafter, the sample is atomized by the atomizing section 12, and the atomized sample, together with a suitable fuel gas and air or other combustion-supporting gas, are directed through the barrel 14 to the grid section 16 to produce a flame 20. The flame is analyzed by the detection system 18 to determine particular characteristics of the sample.

The instrument is supplied with natural gas from a gas main indicated schematically at 25. The main 25 is subject to normal pressure fluctuations which vary over a comparatively wide range. To provide a rough control over extreme variations in pressure, the main is connected to a pressure regulator 26. From the regulator 26 the fuel gas is led through a flow control valve 27 to a venturi nozzle 30.

Air under pressure also is introduced into the venturi nozzle 30 from a compressor 31, a filter 32, a pressure regulator 33 and a conduit 34. A separate conduit 40 supplies air directly from the regulator 33 to the atomizer-burner. In some embodiments, the venturi nozzle 30 is physically separate from the atomizer-burner and is connected thereto by a conduit 35. In other advantageous arrangements, however, the nozzle 30 forms an integral part of the atomizer-burner structure. Thus, as shown in FIG. 2, the atomizing section 12 comprises a block-shaped housing 37 which includes a centrally located chamber 38 and a venturi passage 39 in spaced relationship therewith. The chamber 38 is supplied with compressed air from the pressure regulator 33 (FIG. 1) through a nipple 41 (FIG. 3). A portion of the incoming air is led to the venturi passage 39 through a laterally extending passage 43. The fuel gas is supplied from the valve 27 to a nipple 45 which communicates with the venturi passage 39 intermediate its ends.

Mounted within the venturi passage 39 is a hollow needle 47. One end of the needle 47 is positioned to receive compressed air from the passage 43, while the opposite or discharge end of the needle is located somewhat beyond the point at which the fuel gas enters the venturi passage 39. Access to the needle 47 and the passageway 39 is provided by a removable plug 48. The end of the passage 39 opposite that connected to the passage 43 communicates with the uppermost portion of a recess 49 in the housing 37.

A stainless steel sample tube 50 extends from within the funnel-shaped container 10 through the central chamber 38 of the atomizing section 12 and is held in place by a plug 51. The tube 50 protrudes into the lower end of the barrel 14 and is surrounded by an atomizing nozzle 52 in spaced relationship therewith. The chamber 38 communicates with the space between the tube 50 and the nozzle 52 to permit an annular stream of compressed air to be directed into the barrel.

The barrel 14 is supported at its lower end within the portion of the housing 37 immediately adjacent the annular recess 49. The barrel 14 slopes upwardly from the housing 37 at an acute angle with respect to the horizontal, and the upper portion of the barrel is bent to form a vertically extending end 55 leading to the grid section 16.

The interior of the barrel 14 is provided with a tubular screen 57 or other wetting surface adjacent the housing 37. A narrow baffle strip or plate 60 extends in a more or less vertical direction within the barrel 14 a short distance above the atomizing nozzle 52. The plate 60 is of arcuate cross section and is suitably affixed at its lower end to the adjacent portion of the screen 57. The plate is angularly disposed with respect to the axis of the barrel, and its upper end abuts the opposite portion of the screen. A drain outlet 62 extends through the wall of the housing 37 immediately beneath the lower end of the plate 60.

The upper end of the barrel 14 terminates in a burner head assembly 65 and is provided with a perforated plate or grid 67. A second grid 68 is spaced above the grid 67 and serves to support the flame 20. The assembly 65 includes a chimney 69 of glass or other transparent material which surrounds the flame. A supply of clean air is led directly from the pressure regulator 33 (FIG. 1) to the interior of the burner head adjacent the base of the chimney through a conduit 72.

The detection system 18 includes a lens 75 which is positioned to receive light from a selected part of the flame 20. The light passes through a filter 76 and a second lens 77 to a suitable photocell 78. The photocell 78 illustratively may comprise an iron-selenium cell or a silicon photodiode and is effective to convert the light energy into electrical energy. The electrical energy from the photocell controls a galvanometer 80 or other electrical detector.

When the apparatus is placed in operation, air under pressure is directed from the compressor 31, the filter 32, the pressure regulator 33 and the conduit 34 to the nipple 41 (FIG. 3) leading to the atomizing section 12. As the air enters the section 12, it is split into two streams. The first stream flows through the central chamber 38 and exits in an annular stream through the atomizing nozzle 52 at high velocity. As the air is discharged from the nozzle 52, the resulting drop in pressure draws the sample to be analyzed from the funnel 10 through the tube 50 and into the barrel 14. The rapid flow of air surrounding the sample is effective to atomize the sample and form a fine spray.

The second stream of compressed air moves through the lateral passage 43 and into the needle 47. As this latter stream is discharged from the needle, it undergoes a drop in pressure which is determined by the dimensions of the various parts. As a result of this pressure drop, fuel gas is drawn into the passage 39 at a substantially constant rate irrespective of changes in pressure of the gas. As indicated heretofore, the pressure in the gas main 25 (FIG. 1) may vary over a comparatively wide range. Although the pressure regulator 26 provides a rough control over extremely large changes in pressure, the pressure of the gas as it enters the venturi 30 nevertheless may be subject to variations which, if not controlled, would adversely affect the accuracy of the detected measurements. By diverting a portion of the compressed air supply to the venturi and utilizing the diverted air to draw in the fuel gas, however, the adverse effects of variations in pressure of the fuel gas are eliminated, thus insuring the formation of an extremely constant and well-defined flame.

A further advantage that results from the system described above is that the composition of the air and fuel gas mixture is relatively invariant to changes in air pressure as well as to fuel gas pressure changes. Since the air aspirates its own fuel gas, the air-to-gas mixture ratio is almost independent of air pressure. This ratio remains substantially constant irrespective of pressure fluctuations in either the air or fuel gas supply. Other parameters being equal, the amount of sample atomized and the size

of the flame will vary with changes in air pressure, although these variations are of little moment for several types of measurements. The relative proportion between two different elements in the sample, however, is independent of flame size and amount atomized. Accordingly, in cases in which it is desired to avoid the effects of variations in these characteristics, an internal standard may be included in the sample to enable the realization of an extremely accurate measurement.

The fuel gas and air mixture is directed at a uniform rate from the venturi 30 into the annular recess 49 and then to the barrel 14. The mixture and the atomized sample from the nozzle 52 flow along the barrel to the burner section 16 and pass through the lower grid 67 and then to the flame grid 68, where ignition takes place to produce the flame 20. The flame is viewed through the chimney 69 by the detection system 18. The detected light from the flame is focused on the photocell 78 to produce an electrical signal in response to a selected characteristic of the flame. The signal controls the meter 80 to provide an accurate analytical measurement of the selected characteristic.

As the mixture of air, fuel gas and atomized sample moves along the barrel 14, large droplets of the sample may appear which result either from condensation or incomplete atomization. It is of course desirable to prevent these droplets from reaching the flame 20 and to provide for the efficient removal of the droplets to prevent clogging or otherwise interfering with the atomizer or the fuel gas inlet. Because of the baffle 60 and the bent portion 55 of the barrel 14, the droplets contact the inner side wall of the barrel well prior to reaching the flame. The droplets are rapidly removed through the drain outlet 62 without clogging or otherwise interfering with the atomizing nozzle 52 or the fuel gas inlet from the passage 39. Such removal is facilitated because of the disposition of the barrel 14 at an acute angle with respect to the horizontal in a direction that places the fuel gas inlet on top and the drain outlet 62 on the bottom. The perforated screen 57 or other wetting surface on the inside of the barrel is effective to collect the droplets and facilitate their downward flow toward the outlet 62. The baffle plate 60 provides a protective channel for the downwardly flowing droplets and also helps to collect any large unatomized droplets which issue from the nozzle 52. With this arrangement, the adverse effect of the droplets on the flame, and the necessity for frequent cleaning of the grids are eliminated.

As indicated heretofore, a supply of clean air is led directly to the burner 16 through the conduit 72. This air, which does not contain atomized sample, is directed along the inside of the chimney 69 and helps to prevent the deposit of any unwanted residues thereon.

The sample container 10 comprises a glass funnel which is provided with a drain outlet 85. The outlet 85 includes a bent portion 86 which extends to a level above the lower end of the sample tube 50. The sample within the container and the outlet is in liquid form or in solution and may include an internal standard. The normal level of the liquid in the bent portion 86 is shown schematically in FIG. 2 by the dash line 87. Upon the completion of a given measurement and the insertion of a new sample to be analyzed in the container, the added liquid raises the level within the bent portion 86 and permits the previous sample to be withdrawn automatically by the capillary action of the liquid as it moves through the bent portion and down the tail 88 of the funnel below the level of the trap 89. A small quantity of the additional sample is then added in the container to provide further insurance that the liquid drawn into the tube 50 is an accurate representation of the sample being evaluated.

The inner grid 67 is effective to smooth out and stabilize the flow to the upper grid 68. As a result, an extremely steady flame is produced on the upper grid 68. Each grid is fabricated from a thin perforated plate, thus avoiding

long channels in the grid which exhibit a tendency to collect sample residue and require frequent cleaning.

The terms and expressions which have been employed are used as terms of description and not of limitation, and there is no intention, in the use of such terms and expressions, of excluding any equivalents of the features shown and described, or portions thereof, it being recognized that various modifications are possible within the scope of the invention claimed.

I claim:

1. An analytical instrument comprising, in combination: means containing a sample of material to be analyzed; means for atomizing said sample; a burner in juxtaposition with the atomizing means for producing a flame; means interconnecting said atomizing means and said burner, the atomized sample being directed by the interconnecting means from said atomizing means to said flame; a light sensitive detection system responsive to a characteristic of said flame for making an analytical measurement of said characteristic; venturi means in fluid flow communication with said atomizing means, said venturi means having a venturi passage and a control passage for regulating fluid flow through the venturi passage; means for supplying fuel gas to the venturi passage of said venturi means; and means for supplying pressurized gas to the control passage of said venturi means, the pressurized gas supplied to said control passage drawing said fuel gas into said venturi passage at a rate proportional to the rate of flow of the pressurized gas.

2. An analytical instrument comprising, in combination: means containing a sample of material to be analyzed; means for atomizing said sample; a burner in spaced juxtaposition with the atomizing means for producing flame; means interconnecting said atomizing means and said burner, the atomized sample being directed by the interconnecting means from said atomizing means to said flame; a light sensitive detection system responsive to a characteristic of said flame for making an analytical measurement of said characteristic; venturi means in fluid flow communication with said atomizing means; means for supplying fuel gas to said venturi means; and means for supplying combustion supporting gas to said venturi means, said venturi means mixing said combustion supporting gas with said fuel gas and maintaining the mixture ratio of said combustion supporting gas and said fuel gas substantially constant irrespective of pressure fluctuations in the fuel gas supply.

3. An analytical instrument comprising, in combination: means containing a sample of material to be analyzed; means for atomizing said sample; a burner in spaced juxtaposition with the atomizing means for producing a flame; barrel means interconnecting said atomizing means and said burner, the atomized sample being directed through the barrel means from said atomizing means to said flame; a light sensitive detection system responsive to a characteristic of said flame for making an analytical measurement of said characteristic; venturi means in fluid flow communication with said atomizing means; means for supplying fuel gas to said venturi means; and means for supplying pressurized gas to said venturi means, said pressurized gas exhibiting a drop in pressure as it passes through said venturi means, said venturi means drawing said fuel gas through said venturi means at a rate substantially controlled by said drop in pressure.

4. An analytical instrument of the character set forth in claim 3, in which a portion of said barrel means is angularly disposed with respect to the horizontal.

5. An analytical instrument of the character set forth in claim 3, in which said barrel means comprises an elongated tube, and means defining a wetting surface on a portion of the interior wall thereof.

6. An analytical instrument of the character set forth in claim 5, which further comprises: baffle means disposed within said tube for deflecting unatomized sample toward said interior wall.

7. In an atomizer burner, in combination:
means containing a sample of material to be atomized;
means for atomizing said sample;
a burner in spaced juxtaposition with the atomizing means for producing a flame;
barrel means interconnecting said atomizing means and said burner, the atomized sample being directed through the barrel means from said atomizing means to said flame;
venturi means in fluid flow communication with said atomizing means, said venturi means having a venturi passage and a control passage for regulating fluid flow through the venturi passage;
means for supplying fuel gas to the venturi passage of said venturi means; and
means for supplying combustion supporting gas at substantially constant pressure to the control passage of said venturi means, the combustion supporting gas supplied to said control passage drawing said fuel gas into said venturi passage at a substantially constant rate.

8. In an atomizer burner, in combination:
means containing a sample of material to be atomized;
housing means including an atomizing nozzle and a drain outlet;
means for transmitting sample from the container means to said housing means; said sample being atomized by said atomizing nozzle;
a burner in spaced juxtaposition with the housing means for producing a flame;
barrel means interconnecting said housing means and said burner, the atomized sample being directed through the barrel means from said atomizing nozzle to said flame;
venturi means mounted within said housing means, said venturi means having a venturi passage and a control passage for regulating fluid flow through the venturi passage;
means for supplying fuel gas to the venturi passage of said venturi means; and
means for supplying combustion supporting gas at substantially constant pressure to said housing means and into the control passage of said venturi means, the combustion supporting gas supplied to said control passage drawing said fuel gas into said venturi passage at a substantially constant rate.

9. In an atomizer burner of the character set forth in claim 8, said housing means including a plurality of passages for dividing said combustion supporting gas into separate streams, one of said streams being supplied to the control passage of said venturi means and the other stream being supplied to said atomizing nozzle to atomize said sample.

10. An analytical instrument comprising, in combination:

means containing a sample of material to be analyzed;
housing means including an atomizing nozzle and a drain outlet;
means for transmitting sample from the container means to said housing means; said sample being atomized by said atomizing nozzle;
a burner in spaced juxtaposition with the housing means for producing a flame;

barrel means interconnecting said housing means and said burner, the atomized sample being directed through the barrel means from said atomizing nozzle to said flame, a portion of said atomized sample tending to form undesired droplets of sample material within said barrel means;

a light sensitive detection system responsive to a characteristic of said flame for making an analytical measurement of said characteristic;

venturi means communicating with said housing means, said venturi means having a venturi passage and a control passage for regulating fluid flow through the venturi passage;

means for supplying fuel gas to the venturi passage of said venturi means;

means for supplying combustion-supporting gas to the control passage of said venturi means, the combustion-supporting gas supplied to said control passage drawing said fuel gas into said venturi passage at a rate proportional to the rate of flow of the pressurized gas; and

means mounted within said barrel means for directing said undesired droplets toward said drain outlet.

11. An analytical instrument of the character set forth in claim 10, in which the means for supplying combustion supporting gas includes a plurality of conduits, one of said conduits being directly connected to the control passage of said venturi means and another of said conduits being directly connected to said burner.

12. An analytical instrument comprising, in combination:

means containing a sample of material to be analyzed;
housing means including an atomizing nozzle and a drain outlet;

means for transmitting sample from the container means to said housing means; said sample being atomized by said atomizing nozzle;

a burner for producing a flame;

barrel means interconnecting said housing means and said burner, the atomized sample passing through said barrel means to said flame, said barrel means including an elongated tube having a first portion extending at an angle with respect to the horizontal and a second portion which is angularly disposed relative to said first portion, the sample within said barrel means tending to form undesired droplets of sample material in the first portion of said tube;

a light sensitive detection system responsive to a characteristic of said flame for making an analytical measurement of said characteristic;

venturi means mounted within said housing means and having a fuel gas outlet leading to said barrel means, said fuel gas outlet being spaced apart from said drain outlet;

means for supplying fuel gas to said venturi means;

means for supplying combustion-supporting gas to said housing means and into said venturi means; and

means mounted within said barrel means for directing said undesired droplets toward said drain outlet.

13. An analytical instrument of the character set forth in claim 12, which further comprises:

a first grid mounted in the path of the mixture of fuel gas and atomized sample for smoothing the flow of said mixture toward said flame; and

a second grid carried by said burner for supporting said flame.

14. An analytical instrument of the character set forth in claim 12, which further comprises: screen means on the interior wall of the first portion of said elongated tube for facilitating the flow of said undesired droplets toward said drain outlet.

15. An analytical instrument of the character set forth in claim 14, which further comprises: plate means supported within the first portion of said elongated tube for

channeling the undesired droplets toward said drain outlet.

16. In an atomizer burner, in combination:

a container for a sample of material to be atomized, said container including an outlet having a trap portion, a bent portion and a discharge end at a level below said trap portion;

housing means including an atomizing nozzle;

conduit means for transmitting sample from the container to said housing means, said conduit means having an end disposed within said container at a level below the bent portion of the container outlet for receiving said sample, the received sample being directed by said conduit means to said housing means and atomized by said atomizing nozzle;

a burner in juxtaposition with the housing means for producing a flame;

barrel means interconnecting said housing means and said burner, the atomized sample being directed through the barrel means from said atomizing nozzle to said flame, said barrel means comprising two sections which meet at an angle;

a light sensitive detection system responsive to a characteristic of said flame for making an analytical measurement of said characteristic;

means for supplying fuel gas to said housing means; and

means for supplying combustion supporting gas to said housing means.

17. In an atomizer burner of the character set forth in claim 16, in which said container comprises a funnel containing said sample.

18. An analytical instrument comprising, in combination:

a container for a sample of material to be analyzed, said container including an outlet having a trap portion and a discharge end at a level below said trap portion;

means for atomizing said sample;

a burner in juxtaposition with the atomizing means for producing a flame;

barrel means interconnecting said atomizing means and said burner, the atomized sample being directed through the barrel means from said atomizing means to said flame, said barrel means comprising two sections which meet at an angle;

a light sensitive detection system responsive to a characteristic of said flame for making an analytical measurement of said characteristic;

venturi means communicating with said atomizing means;

means for supplying fuel gas to said venturi means; and

means for supplying pressurized gas to said venturi means, said pressurized gas exhibiting a drop in pressure as it passes through said venturi means, said venturi means drawing said fuel gas through said venturi means at a rate substantially controlled by said drop in pressure.

19. An analytical instrument of the character set forth in claim 18, in which the fuel gas supply includes a pressure regulator for controlling the pressure of said fuel gas prior to the time it reaches said venturi means.
